UNITED STATES PATENT OFFICE.

HENRY H. WILLIAMS, OF PHILADELPHIA, PENNSYLVANIA, ASSIGNOR TO THE TABOR MANUFACTURING COMPANY, OF PHILADELPHIA, PENNSYLVANIA, A CORPORATION.

BURNER.

Application filed July 11, 1923. Serial No. 650,766.

While the heavy petroleum oils compare favorably with coal as to cost per heat unit contained in the fuel and are much cleaner, easier and cheaper to handle, they have not come into general use in domestic heating plants because of the inadequacy of the apparatus offered commercially for this purpose to meet the conditions presented.

One of the difficulties incident to the operation of oil burners of the type used in furnaces for domestic heating and for the generation of heat on a larger scale relates to the danger and inconvenience resulting from the continued flow of fuel after the burner has been inadvertently extinguished.

Other difficulties relates to obtaining economical and, therefore, complete and uniform combustion of the fuel and to the automatic regulation and control of the burner as to the amount of heat generated and as to the air supplied to support combustion.

In the apparatus which embodies the present invention, as shown, the fuel supply is entirely dependent on the operation of the burner, being fed by the slight vacuum created by the burner nozzle jet and lifted thereby from the fuel supply tank so that the fuel supply ceases as soon as combustion at the nozzle stops and the burner and parts in the vicinity of the burner are cooled a few degrees below their operative condition.

One feature of the invention relates to the thermostatic regulation, or, control of the heat generated, such regulation being accomplished through the agency of the vacuum which moves the fuel supply, another feature to the control of the air which supports combustion through the same agency.

On account of the economic necessity for burning low grade fuels, means is provided for heating the fuel as it is fed to the burner so that it flows and atomizes and burns more easily and the invention further relates to the form and arrangement of said heating device.

The apparatus is of the type in which the draught is created and the fuel is atomized by means of a steam jet in the burner and, in the present instance, the steam for this purpose is generated by heat of the burner which consists of a pilot burner which operates continuously and one or more intermittent burners controlled by a thermostat or by hand. Steam for the jet is con-

veniently provided by the pilot burner so 55 the steam for this purpose is always available, and the fuel is preferably heated locally by a coil in the fuel tank in the immediate vicinity of the point from which the oil is drawn for the burners, the hot water or 60 steam pipes leading to the coil and the oil pipes leading to the burners being closely assembled, the group of pipes being preferably enclosed within an insulating covering to increase the efficiency of heating the 65 fuel.

In the form of the apparatus illustrated, the coil which heats the fuel is connected to a coil or equivalent heating unit in the vicinity of the burner and the water for heating the fuel is connected to the steam coil supplying water thereto to create steam for the burners. Air to support combustion is drawn in through a suitable opening, the same being controlled by a damper in the 70 vicinity of the burner which, in accordance with the preferred form of invention is controlled by the vacuum created by one of the intermittent burners, so that the draught opening is always proportionate to the 75 amount of fuel burned and may, therefore, be so regulated as to be just sufficient to support the combustion of the varying quantity of fuel presented, the air supply varying as the amount of fuel presented varies. 85

In the accompanying drawings, I have illustrated an oil burner embodying the features of my invention in what I regard as the preferred form.

In the drawings:

Figure 1 is a diagrammatic view illustrating the entire system, certain features being distorted so as to show the different parts and the manner of connecting them, though the parts as illustrated are not all in their 95 operative relation.

Figure 2 is an elevation of the burner apparatus looking from the front of the furnace, a fragment of the tank being also shown.

Figure 3 is a central, vertical section taken at right angles to Figure 2, showing the burner and water pipes in elevation.

Figure 4 is an elevation looking at the burner from the front of the furnace.

Figure 5 is a vertical, central section taken at right angles to the plane of Figure 4.

Figure 6 is an enlarged vertical section

through one of the burner plugs or nozzles showing fragments of the burner casting in the vicinity.

Figure 7 is an elevation looking at the burner from the right as seen in Figure 5.

Figure 8 is a horizontal section through the center of the burner casting.

Figure 9 is a fragmentary section through the fuel tank, the fuel heating coil and oil pipes and connections being shown in elevation, the latter being broken away intermittently for convenience of illustration.

Figure 10 is a horizontal section on the line 10—10 of Figure 9.

Figure 11 is a fragmentary plan, showing the portion of the fuel tank in which the coil is situated and illustrating the manner of connecting the coil to the tank.

Figure 12 is an elevation of the thermos static controlling apparatus.

Figure 13 is a side view of the same at right angles to Figure 12.

Referring to the drawings by numerals:

The apparatus, as shown, includes a burner, 1, having a pilot nozzle, 2, and an intermittent burner nozzle, 3, a steam coil, 4, in the flame from the pilot nozzle 2, a water heating coil, 5, fuel heating coil, 6, thermos static regulating device, 7, damper, 8, and an automatic damper regulator, 9.

Referring particularly to Figures 2 and 3, the burner proper with the steam and water heating coils and the water filter are mounted on a single plate, 10, which may, to advantage, be secured to the furnace door opening, the plate being in the form of the invention shown supported in the opening on an asbestos bond or frame, 11, which is fastened to the plate, 10, in any suitable manner by means of bolts, 12, and to the furnace walls by some conveniently removable fastening as hook bolts, 13.

In the present instance, the burner casting which may be of circular cross section is situated in a central opening, 15, in the plate, 10, the opening being as shown, surrounded by a boss, 16, the burner casting being secured to the boss by a set screw, 17. The steam and water pipes are also passed through openings in the plate.

Water is led to the apparatus by a pipe, 18, connected to a suitable source of supply and controlled, if the pressure so requires, by a reducing valve, 19. A shut off or globe valve, 20, is also provided to control the water supply. The pipe, 18, leads to a T, 21, the depending arm of the T, or more properly the pipe, 22, connected to the same leads to the water heating coil, 5, which, as shown, is in the form of a semi-circular arc concentric with the burner and spaced a short distance inside the furnace.

The bottom of this coil is connected to a riser, 26, which leads upward from the fuel heating coil, 6, being connected to one end

thereof, the other end of the coil, 6, is connected to a drop pipe, 27, leading from the T, 21.

The water which is turned into steam for use in the burners as described is conditioned by means of a filter, 29, connected to the pipe, 22, by means of a T, 30, the bottom of the filter is connected by a horizontal pipe, 31, which extends through the plate, 10, by way of an opening, 32, with the steam coil, 4, the opposite end of which is connected directly to the burner, 1. The flow of water from the filter to the coil and the back flow of steam are controlled by an orifice, 34, or in any other suitable manner. Oil pipes, 36, and 37 lead upward from the oil tank, 38, in co-operative relation with fuel heating coil, 6, to be described. Beneath the burner and the steam coil and part of the hot water coil, I have shown a pan, 35, to receive priming fluid, as alcohol or gasoline for use in starting the burner.

Referring now to details of the oil burner casting, 1, illustrated particularly in Figures 4 to 8, this casting as shown, is circular in cross section and of generally cylindrical form, with a circumferential shoulder, 138, at one end, however, the external formation of the burner is not of importance except that it provides a pivot for the damper shutter to be described, which might be otherwise supported.

At the opposite end, the burner casting is provided with two burners, nozzles or burner openings, 40 and 41, for the pilot and intermittent burners respectively. These nozzles are similar. They may be pushed into holes, 42, suitably formed in the end of the casting to receive them. Each nozzle has a discharge opening, 43, or fuel nozzle of frusto-conical formation, the diameter increasing toward the outer end. This discharge opening which is a frusto-conical cavity, is flat at the inner or small end, forming a shoulder or offset, 44, surrounding the discharge end of the steam nozzle, 45, which is also frusto-conical and of smaller diameter having its small end opening into the center of the small end of the fuel nozzle opening. The fuel feed passage, 46, is at right angles to the axes of the frusto-conical portions which, as shown, are in alignment. It enters the small end of the frusto-conical portion which we have referred to as the fuel nozzle, at the side thereof.

Fuel is supplied to each of the burners by passages, 47, one for each nozzle extending in the direction of the axis of the burner casting from the rear end thereof each to a point adjacent the side of the corresponding burner opening. Each passage, 47, 48, is connected, in any suitable manner as shown, to the fuel supply passage, 46, leading to the corresponding burner.

The fuel passages, 47, 48, are connected to

oil pipes, 36 and 37, as shown, the oil being lifted by the vacuum created by the flow of steam through the nozzle, by the shoulder, 44, as hereinafter described.

5 Referring particularly to Figure 4, it will be noted that the fuel supply which, as aforesaid, is raised, controlled and atomized by the steam jet is led to the intermittent nozzle, 42, by a fuel passage, 48, which is connected to the outside of the burner casting by two passages, 51 and 52, this being in addition to the connection to the fuel pipe, 37. The passage, 51, is connected to the damper control and the passage, 52, is controlled by the thermostat in turn controlling the fuel supply to the intermittent nozzle by breaking at controlled intervals the vacuum which lifts the fuel thereto.

20 Referring now to Figures 12 and 13 and to the diagram, Figure 1, the operation of the burner may, to advantage, be automatically controlled by the thermostatic apparatus, 7, illustrated in detail in these figures. This consists of a thermostatic coil, 55, to be placed in the apartment being heated, it being understood that the thermostatic control described is ordinarily applied to the heating of dwellings, though the burner may be similarly controlled for other purposes.

25 The central or inner end of the thermostatic coil, as shown, is secured to a sleeve, 56, rotatably mounted on a stud or bolt, 57, secured to the base plate, 58. As shown, the sleeve is provided with a radially projecting arm, 59, to the end of which a thumb screw, 60, is connected as by a swivel, 61, the thumb screw, 60, being mounted at right angles to the arm, and having a threaded engagement with a stationary nut, 62, which may be secured to the base, 58, as shown. The screw provides for adjustment of the thermostat in an obvious manner by turning the center of the coil in either direction. The other end of the thermostatic coil is secured to a swinging arm, 63, pivoted at 30 64, on the base plate, 58, in any suitable manner, and carrying at its free or swinging end, 65, a valve member, 66, which operates with the open end of the vacuum pipe, 68, which is connected at its other end to the opening, 52, in the burner which leads to the fuel passage, 47, of the intermediate burner, as described.

35 It will be understood that as the fuel is sucked up from the supply by the vacuum created in the passage, 46, by the jet from the steam nozzle, 45, so long as the burner is in operation, there must be a vacuum or sub-atmospheric pressure in the fuel pipe, 47, and hence in the vacuum pipe, 68, and it is through this agency that the thermostat controls the operation of the intermittent burner, and the thermostat being set to maintain a given, normal temperature, lifts the valve, 66, from its seat, 70, opening the pipe, 68,

whenever the temperature goes above normal, breaking the vacuum by admitting air to the pipe, 68, and extinguishing the intermittent burner by discontinuing the fuel supply thereto.

40 On the other hand, if the temperature drops below the normal for which the thermostat is set, the valve, 68, is returned to its seat by the action of the thermostatic coil, tending to swing the arm, 63, to the right, as seen in Fig. 12.

45 It will be understood that the pilot, 40, burns continuously, keeping the coil, 4, hot and maintaining the supply of steam to the nozzles, so that as soon as the valve, 68, is returned to its seat, 70, the pipe, 68, being thus closed, the vacuum is again set up by the action of the steam jet and almost immediately a supply of fuel is raised from the tank by the vacuum in the fuel supply passage, 48, so that the fuel being presented in the path of the steam jet is atomized, producing a jet of vapors mixed in combustible proportions, which is immediately ignited by the pilot, it being understood that the regulation referred to relates entirely to the intermittent burners, it being found desirable to have the operation of the pilot burner constantly maintained throughout the period during which heat is desired.

50 The thermostatic apparatus, 7, also includes a gauge which is conveniently placed in the apartment being warmed by the heating apparatus, which gauge serves to indicate the depth of the oil in the tank, so that it is not necessary to examine the tank or to go near it to determine the condition of fuel supply. The gauge, 72, referred to is a pressure gauge connected to the vacuum pipe, 68. This is shown in the vicinity of the thermostat. The gauge is connected to the pipe, 68, by a T, 73, and an upright, 74. It will be apparent that when the intermittent burner is in operation, the sub-atmospheric pressure or vacuum in the pipe, 68, will be, to a degree, proportionate to the distance of the top level of the oil in the tank below the burner. Therefore, the higher the vacuum, the lower the level of the oil in the tank, so that by properly graduating the gauge, the approximate condition of the oil supply as to the quantity thereof may be indicated on the gauge. I have also shown a pet cock, 75, in the vicinity of the gauge and the thermostat whereby the air may be let into the vacuum pipe, 68, at will, breaking the vacuum and cutting off the oil supply to the intermediate burner, extinguishing the same.

55 The air supply to the burner may, to advantage, be automatically regulated by the damper, 8, actuated by the suction or vacuum which lifts the fuel, the damper being opened and closed according to the rate and periods of combustion in the intermittent burner. The damper, 8, in the form of the invention

- shown, is opened and closed by a Bourdon tube, 9, the open end of which, 77, is connected directly to the opening, 51, in the burner, see Figure 4, which leads to the fuel passage, 48, which supplies the intermittent burner and the tube is supported by the burner casting, the other end of the Bourdon tube, 9, being connected to the rotary portion of the damper or shutter.
- 10 It is apparent that the variation of the pressure in the tube corresponds to the rate and periods of combustion at the intermittent burner and will produce corresponding movements of the damper.
- 15 The moving member of the damper, 8, which is in the form of a circular shutter, 82, is pivoted on the burner casting and is provided with an adjustable stop, 81, and there is a fixed stop, 79, on the plate, 10, to 20 co-operate therewith in open position of the shutter, and a second fixed stop, 80, on the shutter which contacts the fixed stop, 79, when the shutter is closed. The rotary member, 82, is provided with arcuate slots, 83, 25 84, 85 to permit the swinging of the rotary member or shutter relatively to the pipes, 22, 26 leading to the coil, 5, and 31, leading to the coil, 4. The rotary shutter is provided with radial slots, 86, and the stationary plate, 10, is provided with corresponding slots, 87. The slots are in registration when the damper is open, the stop, 81, being in contact with stop, 79. The adjustment of the stop, 81, provides for variation of the 30 opening.
- I have referred in a general way to the heating of the oil in the tank locally in the immediate vicinity of the intake ends of the oil pipes, 36 and 37, which lead to the fuel 35 passages, 47, in the burner.
- The local heating of the oil referred to is accomplished by means of coil, 6, which is termed the fuel or oil heating coil and which surrounds the intake ends of the oil pipes, 40 45 36 and 37. The respective ends of this coil, 6, are connected to pipes, 26 and 27, the pipe, 26, leading to the water heating coil, 5, and pipe, 27, being connected to the T, 21, see Figure 2, which, in turn, is connected to 50 the upper end of the coil, 5, by the pipe, 22, and to the water supply by the pipe, 18. The connections thus outlined provide for thermosiphonic circulation of the water upward through the coil, 5, and the pipe, 22, 55 and downward through the pipe, 27, and the coil, 6, and upward from the coil, 6, through the pipe, 26, to water heating coil, 5.
- To increase the heating effect of the coil, 60 the oil pipes, 36 and 37 are assembled in close relation with water pipes, 26 and 27, leading to and from the oil heating coil, 6, see Figure 10, and the pipes thus assembled are covered externally of the group of pipes with heat insulating material, 90, and these 65 pipes, with the insulation, are enclosed with- in a length of larger pipe, 91, which is closed at the lower end by a pipe cap, 92, suitably bored to admit the pipes or tubes 26, 27, 36 and 37. The upper end of the pipe, 91, is equipped with a bushing, 93, which, 70 as shown, is externally threaded and provided at its upper end with a hexagonal portion, 94, to be conveniently engaged by means of a wrench. As shown, the bushing is tapered as to the threaded portion, 95, and adapted to engage a threaded opening, 96, in a flange or plate, 97, secured to the tank, covering and surrounding an opening, 98, in the top wall of the tank.
- Figure 9 illustrating this feature is 80 broken away for convenience of illustration to reduce the length of the pipe, 91, and the parts enclosed therein. The coil, 6, and the bottom ends of the pipes 36 and 37 are placed near or at the bottom of the tank to 85 enable the oil pipes to withdraw substantially all the oil in the tank, and the pipe, 91, with the enclosed parts extends upward from this point to the top of the tank, being, therefore, of a length proportionate to the 90 depth of the tank so that the hot water pipes, 26 and 27, are in contact with the oil pipes 36 and 37 throughout a considerable portion of their length noticeably increasing the efficiency of the transfer of heat from 95 the water to the oil about to be burned.
- It will be noted from examination of Figure 9 that the fuel heating apparatus, as thus assembled, with its connections and the oil pipes enclosed within the pipe, 91, forms 100 a single integral heating unit, which, with suitable fittings, may be connected disconnected, and removed for inspection or repair and replaced without difficulty.
- The oil pipes, 36 and 37 are preferably 105 provided with strainers, 99 and 100, which are shown adjacent the burner casting. These strainers may be of any preferred type in accordance with the present practice in straining oils and gasoline.
- In the operation of the burner, the pan, 35, is charged with any suitable priming fluid, as gasoline or denatured alcohol. This is lighted and the water turned on, steam is formed in the steam coil or tube, 4, the back 110 flow being checked by the orifice, 34; a steam jet is formed at both nozzles and the steam jet draws oil from the tank. The oil is fed through the passages, 47 and 48, and the vacuum passages 46, to the nozzles forming jets of inflammable mixed vapors, i. e. steam and atomized oil. These jets are lighted by the flame from the pan almost as soon as they are formed, increasing the heat available for the steam coil and hence increasing the jet and suction which feeds the fuel and hence increasing size and heat generating power of the flame. If, as assumed, the cock, 75, is closed and the thermostat, operatively connected, the intermittent burner 115

will go into operation simultaneously with the pilot burner.

Under any circumstances, if the thermostat is in operation, the intermittent burner 5 will be thrown into and out of operation by the opening and closing of the pipe, 68, by means of the valve, 65, making and breaking the vacuum in said pipe, the conditions as to sub-atmospheric pressure in said pipe being 10 transmitted to fuel passage, 47, or vice versa, with the result that the fuel supply to the intermittent burner is varied, in accordance with the heating requirements as indicated by the thermostat.

15 As aforesaid, the thermostat may be regulated as to normal temperature by means of the screw, 60, and the fuel conditions as to the extent of the supply in the tank are indicated by the gauge, 72.

20 The manner of the circulation of the water through the water heating coil, 5, adjacent to the burner and from this coil to and from the fuel heating coil, has been fully discussed above. The water is led from the drop pipe 25 tube, 22, to the filter, 29, and hence to the steam coil, 4, by way of the orifice, 34, which regulates the supply of water to the steam coil and prevents back flow of steam therefrom. The steam as generated in the steam 30 coil by the heat of the pilot or both burners serves to build up jets in both burners sufficiently to lift the fuel from the tank to the respective burners and when both burners are in operation, the steam pressure is correspondingly increased.

35 Feeding the fuel in this way, i. e., by the vacuum created by the steam jet, prevents accumulation of oil in the furnace when either or both burners are extinguished. 40 either accidentally or in the case of the intermittent burner during regulation by the thermostat. This arrangement makes regulation in this way conveniently possible and under all circumstances even in the absence 45 of regulation results in greatly increased safety of operation and eliminates all chance of explosion. It is of course apparent that an equivalent intermittent feed may be obtained provided any point in the feed pipe 50 be above the level of the liquid in the tank even though the burner thus fed be below such level, the main point to be emphasized in the feed being that the fuel must be raised by the suction at least in starting so that breaking the vacuum at the proper point 55 stops it.

An important feature of the invention resides in the arrangement whereby forced draught and automatic operation are provided without outside power, no electricity, steam pressure or high pressure water supply being necessary, the burner apparatus 60 being entirely complete in itself, generating its own steam for the burner jets and for 65 raising the fuel and vacuum regulation. Al-

so the water for heating the fuel is heated by the burner, and circulated by the heat of the burner, so that no outside agencies are involved in the operation other than providing fuel and water and starting and stopping it at the beginning and end of the 70 periods during which heat is desired.

It is also important that I have not only utilized the vacuum of the burners to feed the fuel thereto, but have utilized this vacuum to control the air draught thereto in the manner described and have further used it as a means for applying thermostatic regulation to the burner.

Heating of the oil locally and on the way 80 to the burners in the manner described, not only serves to condition low grade fuels so that they are easily moved, atomized and burned giving complete combustion, but economizes heat and improves the operation 85 of the burner to a high degree, the local heating requiring much less heat and being much quicker than any method by which a considerable portion of the fuel supply is heated at one time.

90 While I have referred to steam as the atomizing fluid, the steam nozzle being otherwise properly termed an atomizing nozzle, I would have it understood that for the purpose of the invention any compressible fluid 95 may be used for atomizing, the term steam being conveniently employed in this connection to distinguish from the fluid fuel and being intended to include any atomizing fluid which may be used in this way. The 100 atomizing medium should preferably be under pressure obtained by heating it or in any other convenient manner.

I have thus described specifically and in detail an oil burner embodying my invention in the preferred form, the specific and detailed description being supplied that the nature and operation of the same may be clearly understood. However, the specific 105 terms herein are used descriptively rather than in a limited sense, the scope of the invention being defined in the claims.

110 What I claim and desire to secure by Letters Patent is:

1. In a liquid fuel burner a combined 115 steam and fuel nozzle, means for supplying steam under pressure to the nozzle, a fuel passage leading to the nozzle, the steam jet tending to maintain a vacuum in said passage, means for maintaining a fuel supply 120 with connections from said fuel supply to said passage whereby the fuel is fed to the fuel nozzle, means enclosing said burner nozzle, means for controlling the air draught, including an air passage and a 125 moving shutter controlling the same, means for actuating said shutter comprising a Bourdon tube connected to the moving shutter member, and a passage connecting the Bourdon tube to the steam passage whereby 130

a corresponding vacuum is set up in the Bourdon tube.

2. A liquid fuel burner comprising a steam nozzle and a fuel nozzle, means heated by the burner for supplying steam under pressure to the steam nozzle, the steam nozzle having a discharge opening adjacent the fuel nozzle, whereby it projects a steam jet into the fuel nozzle, a fuel passage leading to the fuel nozzle whereby the steam jet tends to maintain a vacuum in the fuel passage, a fuel container below the level of the burner, means for leading fuel from the container to the fuel passage, a coil in the vicinity of the burner heated thereby, a coil in the fuel container immediately surrounding the end of the fuel pipe, the remainder of the tank space being unheated, so that the heating of the fuel is confined to the immediate vicinity of the end of the fuel pipe, and means connecting said coils providing for circulation of liquid from one to the other and a connection from said coils to the steam supplying means.

25 3. A liquid burner comprising a steam nozzle and a fuel nozzle, means heated by the burner for supplying steam under pressure to the steam nozzle, the steam nozzle having a discharge opening in the rear of the fuel nozzle whereby it projects a steam jet into the fuel nozzle, a fuel passage leading to the fuel nozzle at the side of the steam jet whereby the latter tends to maintain a vacuum in the fuel passage, a fuel container below the level of the burner, means for leading fuel from the container to the fuel passage, a coil in the vicinity of the burner and heated thereby, a coil in the fuel container surrounding the end of the fuel pipe, means for connecting said coils providing for circulation of liquid from one to the other, an air passage leading to the fuel supply passage of the burner, a thermostat, and means actuated thereby to open and close said air pipe, making and breaking the vacuum in the said fuel passage and a connection from said coil to the steam supplying means.

4. A liquid burner comprising a steam nozzle and a fuel nozzle, means heated by the burner for supplying steam under pressure to the steam nozzle, the steam nozzle having a discharge opening in the rear of the fuel nozzle whereby it projects a steam jet into the fuel nozzle, a fuel passage leading to the fuel nozzle at the side of the steam jet whereby the latter tends to maintain a vacuum in the fuel passage, a fuel container below the level of the burner, means for leading fuel from the container to the fuel passage, a coil in the vicinity of the burner and heated thereby, a coil in the fuel container surrounding the end of the fuel pipe, means for connecting said coils providing for circulation of liquid from one to the

other, means for supplying and controlling the air draught therefor, consisting of an air passage, a movable member controlling said passage, a Bourdon tube connected to said movable member to operate the same, and a pipe connecting said Bourdon tube to the vacuum of the fuel supply and a connection from said coils to the steam supplying means.

5. In a liquid burner, a burner member including a burner consisting of a steam nozzle, a fuel nozzle in front of said steam nozzle, the steam nozzle having a discharge opening entering the rear of said fuel nozzle, an offset adjacent said discharge opening, a fuel passage entering said fuel nozzle, beyond said offset, a fuel supply passage leading to said fuel passage and a steam passage adjacent said fuel passage and connected to said steam nozzle, means heated by the burner for supplying steam to said steam passage, means for maintaining a supply of liquid fuel below the level of the burner, means connecting said burner supply passage thereto, an air pipe connected to said fuel supply passage, a thermostat, means controlled thereby opening and closing said air pipe, a pilot burner, and means for supplying fuel thereto.

6. In a liquid burner, a burner member including a burner consisting of a steam nozzle, a fuel nozzle in front of said steam nozzle, the steam nozzle having a discharge opening entering the rear of said fuel nozzle, a shoulder beyond said discharge opening, a fuel passage entering said fuel nozzle, beyond said shoulder whereby the steam flow creates a vacuum therein, a fuel supply passage leading to said fuel passage and a steam passage adjacent said fuel supply and connected to said steam nozzle, means heated by the burner for supplying steam to said steam passage, means for maintaining a supply of liquid fuel below the level of the burner, means connecting said fuel-supply passage thereto, an air pipe connected to the feeding side of the burner nozzle, a thermostat, means controlled thereby, opening and closing said air pipe, a container in the vicinity of the burner for heating liquid, a container in the fuel supply adjacent the fuel passage, and means connecting the said containers providing for circulation of liquid from one to the other, a connection from said steam passage to said containers.

7. In a liquid fuel burner member a burner comprising a frusto-conical steam nozzle and a frusto-conical fuel nozzle, the small ends of the two frusti being connected, the small end of the fuel nozzle being larger than the corresponding end of the steam nozzle, providing a shoulder surrounding the latter, a fuel passage leading to said small end of the fuel nozzle, a fuel supply passage leading to said fuel passage, a steam space

connected to said steam nozzle, a pilot burner similarly constructed, and a fuel supply leading to said pilot burner, said steam space surrounding part of said fuel passage, means heated by the pilot for supplying steam to said steam space, means for maintaining a fuel supply below said burner, pipes leading to said fuel supply passages, an air pipe leading to the first mentioned fuel supply passage, and a thermostatic valve controlling said air pipe.

8. A liquid fuel burning apparatus including a burner having a fuel nozzle, a fuel supply and a passage from the fuel supply to said nozzle, a supply of fluid under pressure and means for leading same to said burner and discharging same in the vicinity of the fuel nozzle, creating a vacuum to feed the fuel, a movable draft member controlling the burner, and a Bourdon tube connected to

the fluid passage, setting up a corresponding vacuum in the Bourdon tube and controlling said draft member.

9. A liquid fuel burning apparatus including a main burner having a fuel nozzle, a steam passage leading to the fuel nozzle, a pilot burner, a steam generating member heated by the pilot burner, a fuel supply connected to the fuel nozzle, the steam creating a vacuum leading the fuel to the burner, a movable draft member, a pressure actuated member connected to the feeding side of the burner and controlling the draft member, a valve controlling the vacuum, and a thermostatic member actuating the same, and means for supplying fuel to the pilot burner.

Signed by me at Philadelphia, Pennsylvania, this 21st day of June, 1923.

HENRY H. WILLIAMS.
